US00D853663S

(12) **United States Design Patent** (10) **Patent No.:** **US D853,663 S**
 Song (45) **Date of Patent:** **** Jul. 9, 2019**

(54) **EXPANDABLE PET BOWL**

(71) Applicant: **Xingfu Song**, Shenzhen (CN)
 (72) Inventor: **Xingfu Song**, Shenzhen (CN)
 (**) Term: **15 Years**
 (21) Appl. No.: **29/603,136**
 (22) Filed: **May 7, 2017**
 (51) LOC (11) Cl. **30-03**
 (52) U.S. Cl. **D30/129**
 (58) **Field of Classification Search**

USPC D30/121, 122, 129–133; 119/61.5, 51.01, 119/61.56, 51.03, 59, 62, 63, 51.5, 57.8, 119/74, 61.54, 61.55; 312/204; 248/151, 248/188; 108/156, 153.1–157; 220/6, 220/23.87, 630, 737, 743, 9.4, 495.01, 220/574, 212, 255, 23.83, 606, 657, 8, 220/669, 666, 575; 206/515; D7/586, D7/543, 550.1, 587, 505, 584, 545, 500, D7/553.1–553.8, 546, 555, 556, 504, 565, D7/562, 602, 676, 544, 548, 675, 554.2, D7/551.1, 672, 677, 560, 629; D9/429, D9/425, 603; 43/109; D22/122; 99/430, 99/DIG. 15; D27/106, 113, 114; 229/406; 426/104; D32/29.1; D10/46.2

CLAIM

The ornamental design for an expandable pet bowl, as shown.

DESCRIPTION

FIG. 1 is a front elevational view of an expandable pet bowl showing my new design;

FIG. 2 is a rear elevational view thereof;

FIG. 3 is a left side elevational view thereof;

FIG. 4 is a top plan view thereof;

FIG. 5 is a bottom plan view thereof;

FIG. 6 is a front perspective view thereof;

FIG. 7 is a perspective view of the expandable pet bowl shown configured in one incremental position of collapsed retraction;

FIG. 8 is a perspective view of the expandable pet bowl shown configured in another incremental position of collapsed retraction;

FIG. 9 is a perspective view of the expandable pet bowl shown configured in a nearly fully collapsed position; and, FIG. 10 is a perspective view of the expandable pet bowl in its fully collapsed configuration.

1 Claim, 10 Drawing Sheets# US D853,663 S
